[57] **CLAIM**

The ornamental design for a refrigerated container for alcoholic beverages and mixers or the like, substantially as shown.

DESCRIPTION

FIG. 1 is a rear perspective view of a refrigerated container for alcoholic beverages and mixers or the like, showing our new design;

FIG. 2 is a right side elevational view thereof;

FIG. 3 is a front elevational view thereof;

FIG. 4 is a left side elevational view thereof;

FIG. 5 is a rear elevational view thereof;

FIG. 6 is a top plan view thereof;

FIG. 7 is a bottom plan view thereof;

FIG. 8 is a rear perspective view of a second embodiment of the refrigerated container for alcoholic beverages and mixers or the like shown in FIG. 1;

FIG. 9 is a right side elevational view thereof;

FIG. 10 is a left side elevational view thereof;

FIG. 11 is a front elevational view thereof;

FIG. 12 is a rear elevational view thereof;

FIG. 13 is a top plan view thereof; and

FIG. 14 is a bottom plan view thereof.
